Application May 24, 1944, Serial No. 537,057

11 Claims. (Cl. 62—179)

The present invention relates to absorption refrigeration systems and more particularly to a method of and apparatus for purging non-condensable gases from such systems.

While the method and apparatus of the present invention may be used in other absorption refrigeration systems, it is particularly adapted for use in a system of the type illustrated and described in the United States Letters Patent to Albert R. Thomas et al. No. 2,282,503, entitled Refrigeration. The absorption refrigeration system illustrated in the Thomas et al. patent operates in a partial vacuum and utilizes water as a refrigerant and a saline solution as an absorbent. In such a refrigeration system non-condensable gases may accumulate in the various elements of the system which must be purged periodically. The exact cause of the generation of such non-condensable gases or the place where such gases are generated is not fully understood but the gases appear in all parts of the system and accumulate in the condenser and absorber. As the condenser operates at a higher pressure than the absorber the non-condensable gases may be purged more easily from the condenser than from the absorber.

When purging such refrigeration systems it is the usual practice to connect a vacuum pump to the condenser and withdraw the non-condensable gases therefrom. Such a purging operation requires the attention of an attendant and it is difficult to determine when all of the non-condensable gases have been purged. To insure complete exhaustion of all of the non-condensable gases the operation of the vacuum pump is usually continued after the gases have been exhausted so that some of the refrigerant vapor will be withdrawn from the system. Such accumulative bleeding of refrigerant vapor during successive purging operations will result in an unbalancing of the concentration of the solution in the system.

One of the objects of the present invention is to provide a method of and apparatus for automatically purging non-condensable gases from the system without withdrawing any refrigerant vapor after the gases are purged.

Another object of the invention is to provide a water operated aspirator for withdrawing non-condensable gases from a condenser connected to the refrigeration system and utilizing the cooling water discharged from the condenser for operating the aspirator.

Still another object of the invention is to vary automatically the temperature and vapor pressure of the water for operating the aspirator in

accordance with the presence or absence of non-condensable gases in the condenser to render the aspirator operative to purge non-condensable gases and inoperative to withdraw refrigerant vapor after the gases are purged.

These and other objects will become more apparent from the following description and drawing in which like reference characters denote like parts throughout the several views. It is to be expressly understood, however, that the drawing is for the purpose of illustration only and not a definition of the limits of the invention, reference being had for this purpose to the appended claims. In the drawing:

Fig. 1 is a diagrammatic view of an absorption refrigeration system incorporating the novel features of the present invention, and

Fig. 2 is an enlarged diagrammatic view of the auxiliary condenser and water operated aspirator for automatically purging non-condensable gases from the system.

In accordance with the method of the present invention a water operated aspirator is connected to a condenser in the refrigeration system for purging non-condensable gases therefrom. The condenser is arranged to receive the non-condensable gases and preferably is a separate or auxiliary unit connected to the main condenser of the system. In its broadest aspect the method 25 comprises varying the temperature and corresponding vapor pressure of the water flowing through the aspirator in accordance with the presence or absence of non-condensable gases in the auxiliary condenser. The degree of vacuum or, in other words, the lowest absolute pressure obtainable with a water operated aspirator varies 30 in accordance with the vapor pressure of the water flowing therethrough which, in turn, varies with the temperature of the water. As an example, let it be assumed that a pressure of 53.67 mm. Hg abs. is present in the auxiliary condenser, and that a resistance of 2 mm. Hg exists in the conduit between the condenser and aspirator producing a critical pressure of 53.67 mm. Hg minus 35 2 mm. Hg or 51.67 mm. Hg abs. at which media will flow from the condenser to the aspirator. If water is supplied to the aspirator at a temperature of 100° F. the aspirator will produce a pressure of 49 mm. Hg abs., the vapor pressure of 40 water at 100° F., which is less than the critical pressure of 51.5 mm. Hg so that media will flow from the auxiliary condenser to the aspirator.

However, if water is supplied to the aspirator at 45 102° F. the aspirator will produce a minimum pressure of only 52 mm. Hg abs., the vapor pres- 50 sure of

sure of water at 102° F., which is above the critical pressure of 51.5 mm. Hg so that the aspirator will be inoperative to withdraw media from the condenser.

The vapor pressure of the water flowing through the aspirator is varied in accordance with the presence or absence of non-condensable gases in the auxiliary condenser by utilizing the cooling water discharged from the auxiliary condenser to operate the aspirator. When non-condensable gases are present in the condenser they blanket off the condenser surface which they cover so that less heat will be transferred to the water. The temperature of the water supplied to the aspirator, therefore, will gradually decrease as the amount of non-condensable gases in the auxiliary condenser increases until the comparatively low temperature of 100° F. is reached. At this low temperature the water in the aspirator will have the low vapor pressure of 49 mm. Hg abs., referred to above, so that the aspirator will be effective to produce a vacuum pressure below the critical pressure at which media will flow from the condenser to the aspirator. The non-condensable gases in the condenser then will flow to the aspirator and will be entrained in the water discharged from the aspirator.

However, when the non-condensable gases have been withdrawn from the condenser they will be displaced by condensable refrigerant vapor. The latent heat of the refrigerant vapor will be transferred to the cooling water flowing through the condenser and the vapor will be condensed to a liquid. Due to the heat transferred from the refrigerant vapor to the cooling water the temperature and vapor pressure of the water discharged from the condenser to the aspirator will be increased to the values of 102° F. and 52 mm. Hg abs., respectively, referred to above. When water is supplied to the aspirator at this higher vapor pressure the aspirator will not be effective to produce a vacuum pressure lower than the critical pressure at which media will flow from the condenser. It will now be apparent that by varying the vapor pressure of the water used in the aspirator the latter will be rendered operative to purge non-condensable gases from the auxiliary condenser and rendered inoperative to withdraw refrigerant vapor after the gases have been purged.

Referring to the drawing an apparatus for carrying out the steps of the method is shown applied to a two-pressure absorption refrigeration system similar to that illustrated and described in the Thomas et al. patent, referred to above. In a system of this type liquid refrigerant such as, for example, water is introduced into the upper part of an evaporator or cooling element 10 from a condenser 11 through a path of flow including a U-shaped tube 12 and flash chamber 13. The liquid refrigerant evaporates in the evaporator 10 with consequent absorption of heat from the ambient such as a stream of air flowing over the exterior surface of the tubes 14 and fins 15 of the evaporator. The refrigerant vapor formed in the evaporator 10 flows to an absorber 16 in which the vapor is absorbed into a liquid absorbent such as, for example, a water solution of lithium chloride, lithium bromide or the like.

The absorption liquid enriched with refrigerant is conducted from the absorber 16 to a generator 17 in a path of flow including conduit 18, liquid heat exchanger 19, conduit 20, vessel 21, and conduit 22. Within the generator 17 a plurality of riser tubes 23 are enclosed within a shell 24 form-

ing a chamber to which steam is supplied through a conduit 25 from a suitable source of supply. The heating of the riser tubes 23 by the steam causes refrigerant vapor to be expelled from the absorption solution and the expelled vapor is effective to raise the absorption liquid by gas or vapor-lift action.

5 The expelled vapor passes from the upper ends of the riser tubes 23 into a vapor separating chamber 26 having suitable baffles 27 therein and thence flows through a conduit 28 to the condenser 11 in which the vapor is liquefied. The liquid refrigerant formed in the condenser 11 flows by gravity into the U-shaped tube 12 to the upper part of the evaporator 10 as explained above to complete the refrigeration cycle.

10 The raised absorption liquid from which refrigerant vapor has been expelled is conducted from the upper part of the generator 17 to the absorber 16 to absorb refrigerant vapor, this liquid being conducted to the absorber in a path of flow including a conduit 29, liquid heat exchanger 19, and conduit 30. The heat liberated by the absorption of refrigerant vapor in the absorber 16 is taken up by a cooling medium such as, for example, water which flows upwardly through vertically disposed banks of pipes 31 in the absorber. The cooling water is introduced into the lower end of the banks of pipes through a conduit 32 and is discharged from the upper ends of the banks of pipes through a conduit 33. The conduit 33 is connected to the condenser 11 so that the cooling water also may be utilized to effect cooling of the condenser. The cooling water is discharged from the condenser 11 through a conduit 34.

15 The system operates in a partial vacuum with generator 17 and condenser 11 operating at one pressure and evaporator 10 and absorber 16 operating at a lower pressure. The pressure differential between the high and low pressure sides of the system is maintained by liquid columns in the up-leg of the U-shaped tube 12 between the condenser 11 and the evaporator 10 and in the conduits 18 and 30 connecting the absorber 16 and heat exchanger 19. The liquid level in the U-shaped tube 12 is indicated by the reference character *x*; the liquid levels in the conduit 18 and vessel 21 connected thereto through the heat exchanger 19 are indicated by the reference characters *w* and *y*; and the liquid level in the conduit 29 connected to the conduit 30 through the heat exchanger 19 is indicated by the reference character *z*.

20 25 30 35 40 45 50 55 60 65 70 75 80 85 90 During operation of the refrigeration system non-condensable gases may accumulate in the various elements thereof. These non-condensable gases are probably formed by the chemical action of the fluids with the metallic parts of the system. Any non-condensable gases occurring in the generator 17 are swept into the condenser 11 with the refrigerant vapor flowing thereto at high velocity. The gases in the condenser 11 tend to accumulate adjacent its outlet end. The non-condensable gases in the evaporator 10 are swept into the absorber 16 by the refrigerant as it flows into the absorber at high velocity. The gases then accumulate in a layer at the bottom and center of the absorber 16 where turbulence is at a minimum. Thus, the non-condensable gases accumulate adjacent the outlet from the condenser 11 and at the bottom and center of the absorber 16 and blanket off that portion of the condenser or absorber which they cover.

75 In the embodiment of the invention illustrated

in Fig. 1 of the drawing the non-condensable gases are transferred continuously from the absorber 16 to the condenser 11 by means of a vessel 40 which draws the gases from the bottom of the absorber into the top thereof through a conduit 41. A portion of the absorption liquid flowing to the upper part of the absorber 16 through the conduit 30 is diverted to the bottom of the vessel 40 through a conduit 42. Preferably an apertured septum plate 43 is positioned intermediate the ends of the vessel 40 to provide a measuring orifice for controlling the amount of absorption liquid flowing therethrough. Thus, the diverted absorption liquid is brought into intimate contact with the non-condensable gases drawn into the top of the vessel 40 through the conduit 41. A vertical tube 44, which may be referred to as a fall tube pump, has a curved upper end 45 connected to the vessel 40 above the septum plate 43 with its lower end extending into a separating chamber 46. A conduit 47 is connected to the separating chamber 46 at a point above the lower end of the vertical tube 44 and the opposite end of the conduit is connected to the conduit 18 leading to the heat exchanger 19. A second conduit 48 is connected to the separating chamber 46 at a point above the conduit 47 and the upper end of the second conduit is connected to the conduit 28 between the generator 17 and condenser 11.

Absorption liquid flows into the bottom of the vessel 40 and upwardly through the orifice in the septum plate 43 and into the upper bent end 45 of the fall tube 44 until the liquid siphons into the fall tube. At the end of a siphoning operation small quantities of non-condensable gases in the upper part of the vessel 40 enter the upper bent end 45 of the fall tube 44 and become trapped between successive bodies or slugs of the absorption liquid. The internal diameter of the fall tube 44 is such that gas and liquid cannot pass each other while flowing therethrough and the column of absorption liquid and non-condensable gases maintains the pressure differential between the high pressure and low pressure sides of the system. The non-condensable gases are discharged from the lower end of the fall tube 44 and bubble upwardly through the absorption liquid in the separating chamber 46 which acts to strip any refrigerant vapor therefrom and the gases escape through the conduits 48 and 28 to the condenser 11. The absorption liquid in the separating chamber 46 escapes through the conduit 47 to the conduit 18 of the main circuit of the refrigeration system. Thus, the non-condensable gases in the low pressure side of the system are transferred continuously to the condenser 11 where they accumulate adjacent the outlet end thereof.

In accordance with the present invention the non-condensable gases are purged from the condenser 11 automatically without withdrawing any refrigerant vapor after the gases are withdrawn. The purging apparatus of the present invention may be used in conjunction with any suitable condenser but preferably an auxiliary condenser 50 is provided which is connected to the main condenser 11 adjacent its outlet by means of a conduit 51. The auxiliary condenser 50 is in the form of a cylindrical shell forming a closed chamber and having a water cooled coil 54 therein. Preferably the auxiliary condenser 50 is so constructed and arranged as to condense refrigerant vapor at a temperature slightly lower than

the condensing temperature in the main condenser 11.

The auxiliary condenser 50 is connected to a water operated aspirator 55 in a path of flow 5 including a conduit 56, check valve 57 and conduit 58. The check valve 57 may be of any suitable type for permitting the flow of non-condensable gases from the auxiliary condenser 50 to the aspirator 55 while preventing the flow of 10 atmospheric air to the condenser. The check valve 57 also adds a resistance to the flow of non-condensable gases from the auxiliary condenser 50 and the value of the resistance must be such as to produce a pressure drop between the condenser and aspirator greater than the difference 15 between the condenser pressure and aspirator pressure when no non-conductive gases are present. In the illustrated embodiment of the invention the check valve 57 is shown in Fig. 2 as comprising a cylindrical vessel having a septum plate 59 of a porous ceramic material extending thereacross and provided with a covering body of liquid 60 such as mercury on the side adjacent the aspirator 55. Such a check valve is illustrated and described in detail in the prior co-pending application for United States Letters Patent of Charles Alfred Roswell, Serial No. 481,729, filed April 3, 1943, entitled Valve, now Patent No. 2,363,440, issued November 21, 1944.

20 The aspirator 55 has an inlet port 61 at one end, a restricted throat 62 intermediate its ends through which water is adapted to flow and an outlet port 63 at its opposite end to which a discharge tube 64 is connected. The conduit 58 from the check valve 57 is connected to the aspirator 55 at the restricted throat 62 thereof.

25 The cooling coil 54 within the auxiliary condenser 50 has one end connected to an inlet conduit 66 which, in turn, is connected to the 30 conduit 33 between the absorber 16 and main condenser 11 for supplying cooling water thereto. A conduit 67 connects the outlet from the cooling coil 54 to the inlet port 61 of the water operated aspirator 55. Preferably a manually operable 35 valve 68 is provided in the conduit 66 to regulate the amount of water flowing through the auxiliary condenser 50 and water operated aspirator 55 to compensate for variations in the temperature and pressure of the cooling water supply at 40 different localities. One form of the invention 45 having now been described in detail, the mode of operation of the apparatus is explained as follows.

50 During normal operation of the refrigeration system steam will be supplied to the generator 17 through the conduit 25 which will vaporize refrigerant in the tubes 23. The vaporized refrigerant will rise through the separating chamber 26 and conduit 28 into the condenser 11 where the vapor will condense to a liquid. The liquid refrigerant will flow from the outlet of the condenser 11 through the U-shaped tube 12 and flash chamber 13 into the evaporator 10 where the liquid refrigerant will evaporate to produce refrigeration. Refrigerant vapor in the evaporator 10 will flow 55 to the absorber 16 where it will be absorbed in the absorption solution therein. The dilute absorption solution will flow continuously from the absorber 16 through the conduit 18, heat exchanger 19, conduit 20, chamber 21, and conduit 22 back to the base of the generator 17. Simultaneously the concentrated absorption solution in the separating chamber 26 will flow through the conduit 29, heat exchanger 19, and conduit 30, back into the absorber 16.

55 During the operation of the refrigeration sys-

tem any non-condensable gases occurring in the generator 17 will be carried into the condenser 11 with the refrigerant vapor. Simultaneously any non-condensable gases occurring in the evaporator 10 will be swept into the absorber 16 with the refrigerant vapor and will accumulate at the bottom and center of the absorber where turbulence is at a minimum. During normal operation of the refrigeration system the non-condensable gases at the bottom and center of the absorber 16 will be continuously withdrawn therefrom and transferred to the condenser 11 by means of the vessel 40 and fall tube pump 44. Thus, the non-condensable gases occurring in the various parts of the system will be transferred to the condenser 11 and, being non-condensable, they will flow through the condenser and conduit 51 into the auxiliary condenser 50.

Also during operation of the refrigeration system part of the cooling water flowing through the conduit 33 from the absorber 16 to the condenser 11 will be diverted through the conduit 66 to the cooling coil 54 of the auxiliary condenser 50 and will flow from the cooling coil through the conduit 67 to the inlet port 61 of the water operated aspirator 55. The valve 68 will be initially adjusted to cause the proper amount of water to be supplied to the auxiliary condenser 50 to give the proper temperature differential to the water entering and leaving the latter. Due to the flow of the cooling water through the aspirator 55 a partial vacuum will be created at the throat 62 of a value depending upon the vapor pressure of the water. In other words, the water in the aspirator 55 will vaporize when a predetermined low pressure is reached and the pressure at which the water vaporizes is dependent upon its temperature.

The non-condensable gases flowing into the auxiliary condenser 50 with the refrigerant vapor will gradually accumulate therein. As the gases are non-condensable little or no heat will be transferred from the gases through the cooling coil 54 to the water flowing therethrough. As a result, the temperature of the cooling water discharged from the auxiliary condenser 50 will gradually decrease in proportion to the increasing surface area of the auxiliary condenser blanketed by the non-condensable gases. As the vapor pressure of the cooling water decreases with the temperature the pressure produced by the aspirator will be reduced gradually in accordance with the amount of non-condensable gases in the auxiliary condenser until it is lower than the pressure in the condenser less the pressure drop due to the check valve 57. When this low pressure in the aspirator 55 occurs the non-condensable gases in the auxiliary condenser 50 will flow therefrom through the conduit 56, porous septum plate 59 of the check valve 57 and conduit 58 into the aspirator 55 where they will be entrained in the water passing therethrough and exhausted through the discharge tube 64.

The flow of non-condensable gases from the auxiliary condenser 50 will continue and the gases will be displaced by refrigerant vapor flowing thereto from the main condenser 11. When refrigerant vapor enters the auxiliary condenser 50 heat will flow from the high temperature vapor to the relatively low temperature water in the cooling coil 54 causing the refrigerant vapor to liquefy. Due to the transfer of the latent heat of vaporization of the refrigerant vapor to the cooling water in the cooling coil 54 the temperature of the cooling water will rise which, in

turn, will increase the vapor pressure of the water flowing through the aspirator 55. At the higher vapor pressure the water flowing through the aspirator 55 cannot reduce the pressure at the throat 62 to a value below the critical pressure necessary to cause a flow from the auxiliary condenser 50. As the pressure in the aspirator 55 is above the pressure occurring in the auxiliary condenser 50 less the resistance of the check valve 57 refrigerant vapor will not flow from the condenser to the aspirator. Water vapor from the aspirator or atmospheric air, however, is prevented by the check valve 57 from flowing to the auxiliary condenser 50.

As an example, the following operating conditions of a particular unit are given as illustrative. Case I indicates the conditions when no non-condensable gases are present in the auxiliary condenser and Case II indicates the conditions when the auxiliary condenser is filled to maximum capacity with non-condensable gases.

MAIN CONDENSER CONDITIONS IN BOTH CASE I AND CASE II

25	1. Cooling water inlet	° F.	95
	2. Cooling water outlet	° F.	103
	3. Condensing temperature	° F.	104
	4. Condensing pressure (at 104)	mm. Hg abs.	55.32

Case I

30	A. Auxiliary condenser:		
	1. Cooling water inlet	° F.	95
	2. Cooling water outlet	° F.	102
	3. Condensing temperature	° F.	103
	4. Condensing pressure (at 103° F.)	mm. Hg abs.	53.67
	5. Resistance of check valve	mm. Hg	2
	6. Critical pressure (53.67 mm. Hg-2 mm. Hg)	mm. Hg abs.	51.67
35	7. Difference in pressure between main and auxiliary condensers	mm. Hg	1.65
B. Aspirator:			
	1. Water inlet	° F.	102
	2. Lowest possible pressure (at 102° F.)	mm. Hg abs.	52

Case II

40	A. Auxiliary condenser:		
	1. Cooling water inlet	° F.	95
	2. Cooling water outlet	° F.	95
	3. Actual temperature in auxiliary condenser	° F.	95
	4. Actual pressure in auxiliary condenser (main condenser pressure)	mm. Hg abs.	55.32
45	5. Resistance of check valve	mm. Hg	2
	6. Critical pressure (55.32 mm. Hg-2 mm. Hg)	mm. Hg abs.	53.32
B. Aspirator:			
	1. Water inlet	° F.	95
	2. Lowest possible pressure (at 95° F.)	mm. Hg abs.	42

As the condensing pressure in the main condenser 11 will be maintained substantially constant at 55.32 mm. Hg abs. the actual pressure occurring in the auxiliary condenser 50 will be substantially the same as that in the main condenser when the auxiliary condenser is filled to capacity with non-condensable gases and no condensation can occur. The check valve 57 will add approximately 2 mm. Hg resistance to the flow of gases from the auxiliary condenser 50 so that the critical pressure or, in other words, the actual pressure to be overcome by the aspirator 55 when no gases are present will be 53.67 mm. Hg abs. minus 2 mm. Hg or 51.67 mm. Hg abs. When non-condensable gases are present in the auxiliary condenser 50 water will be supplied to the aspirator at 102° F. which will permit the aspirator 55 to produce a theoretical vacuum pressure of only 52 mm. Hg abs. which is above the critical pressure of 51.67 mm. Hg abs. necessary to cause a flow from the auxiliary condenser 50. Therefore, the aspirator 55 will be inoperative to withdraw refrigerant vapor from the auxiliary condenser 50. While the aspirator may not reach the vapor pressure of the water flowing therethrough, for purposes of description the vapor pressure of

water, which a perfect aspirator will produce, is used in the example as a most extreme condition.

When the auxiliary condenser 50 is completely filled with non-condensable gases the aspirator pressure necessary to cause a flow from the auxiliary condenser 50 will be 55.32 mm. Hg abs. Water will be supplied to the aspirator 55 at a temperature of 95° F. which will theoretically permit a low vacuum pressure of 42 mm. Hg abs. The pressure produced by the aspirator 55 being 10 considerably lower than the critical pressure of 55.32 mm. Hg abs. the non-condensable gases will flow from the condenser to the aspirator.

In actual practice the aspirator 55 will operate at temperature and vapor pressure values between 15 those cited above in Case I and Case II at which time both non-condensable gases and refrigerant vapor will be present in the auxiliary condenser 50. When the temperature of the cooling water in the aspirator 55 decreases to produce a pressure less than the critical pressure of 51.67 mm. Hg abs., referred to in Case I, some non-condensable gas will be withdrawn from the auxiliary condenser 50 and the greater the decrease in the aspirator pressure the greater will be the amount 20 of gas which flows to the aspirator. Thus the temperature and vapor pressure of the cooling water flowing through the aspirator 55 will gradually decrease until a condition of equilibrium is reached at which time the non-condensable 25 gases will be withdrawn from the auxiliary condenser 50 as rapidly as they enter the condenser. The actual pressure produced by the aspirator 55 will be only a few mm. Hg below the critical pressure at which the gases will start to flow to the 30 aspirator.

It will now be observed that the present invention provides a method of and apparatus for automatically purging non-condensable gases from the refrigeration system without withdrawing any refrigerant vapor after the gases have been withdrawn. It also will be observed that the present invention utilizes the cooling water ordinarily used so that the automatic purging mechanism of the present invention will not add to the cost of operation of the system. It still further will be observed that the present invention provides for varying the vapor pressure of the water in a water operated aspirator to a value above or below the critical pressure at which media will flow from the condenser in accordance with the absence or presence of non-condensable gases therein.

While the method and a preferred form of apparatus are herein illustrated and described, it will be understood by those skilled in the art that various changes may be made in the steps of the method and in the construction and arrangement of the parts of the apparatus without departing from the spirit or scope of the invention as set forth with following claims.

I claim:

1. The method of purging non-condensable gases from an absorption refrigeration system having a condenser and a water operated aspirator connected to the condenser which comprises flowing water through the aspirator, and varying the temperature and vapor pressure of the water flowing through the aspirator in accordance with the presence or absence of non-condensable gases in the condenser whereby said aspirator is operative to withdraw non-condensable gases from the condenser and inoperative to withdraw any refrigerant vapor after the gases are withdrawn.

2. The method of purging non-condensable gases from an absorption refrigeration system

5 having a condenser and water operated aspirator connected to the condenser which comprises supplying water to the aspirator at such a temperature that its vapor pressure is above the pressure at which media will flow from the condenser to the aspirator, and decreasing the temperature and vapor pressure of the water supplied to the aspirator in response to the presence of non-condensable gases in the condenser so that the aspirator will produce a pressure below the pressure at which media in the condenser will flow to the aspirator whereby to withdraw the non-condensable gases from the condenser.

3. The method of purging non-condensable gases from an absorption refrigeration system having a condenser and a water operated aspirator connected to the condenser which comprises flowing cooling water through the condenser and aspirator successively to vary the temperature of the water in the aspirator in accordance with the amount of condensation of refrigerant vapor occurring in the condenser, the vapor pressure of the water varying with said temperature to a value above and below the pressure at which media will flow from the condenser to the aspirator whereby said aspirator is operative automatically to withdraw non-condensable gases from the condenser and is inoperative to withdraw refrigerant vapor after the gases have been withdrawn.

4. The method of purging non-condensable gases from an absorption refrigeration system having a condenser and water operated aspirator connected to the condenser which comprises continuously transferring non-condensable gases from the various parts of the system to the condenser, flowing cooling water through the condenser and aspirator successively to vary the temperature of the water in the aspirator in accordance with the amount of condensation of refrigerant vapor occurring in the condenser, the vapor pressure of the water varying with said temperature to a value above and below the pressure at which media in the condenser will flow to the aspirator whereby said aspirator is operative automatically to withdraw non-condensable gases from the condenser and is inoperative to withdraw refrigerant vapor after the gases have been withdrawn.

5. In an absorption refrigeration system in which non-condensable gases occur, a generator, a condenser, an evaporator, an absorber, means interconnecting the elements to provide a closed circuit for the circulation of a refrigerant and absorbent, and an auxiliary condenser connected to said system for receiving and segregating non-condensable gases therein, a water operated aspirator connected to said auxiliary condenser, and means for flowing cooling water through the auxiliary condenser and aspirator successively 60 whereby said aspirator is operative to automatically withdraw non-condensable gases from the condenser without withdrawing refrigerant vapor after the non-condensable gases have been withdrawn.

6. In an absorption refrigeration system in which non-condensable gases may occur, a generator, a condenser, an evaporator, an absorber, means interconnecting the elements to provide a closed circuit for the circulation of a refrigerant and absorbent, an auxiliary condenser connected to said system for receiving and segregating non-condensable gases therein, a water operated aspirator connected to said auxiliary condenser, and means for supplying water in a path of flow 70 through the auxiliary condenser and aspirator

successively, the temperature of the water in the aspirator varying in accordance with the presence or absence of non-condensable gases in the auxiliary condenser to produce a pressure in the aspirator below or above the pressure at which media will flow from the condenser to the aspirator whereby the aspirator is operative to withdraw non-condensable gases from the condenser without withdrawing refrigerant vapor therefrom after the gases have been withdrawn.

7. In a two pressure absorption refrigeration system of the type which operates in a partial vacuum and in which non-condensable gases may accumulate, means for transferring non-condensable gases from the low pressure side to the high pressure side of the system while maintaining the pressure differential, a condenser connected to the high pressure side of said system to receive and segregate the non-condensable gases, a water operated aspirator connected to said condenser, conduits providing a path of flow for water through the condenser and aspirator successively, and a check valve in the conduit connecting the condenser and aspirator.

8. In an absorption refrigeration system having a plurality of elements interconnected to provide a closed circuit for the circulation of a refrigerant and absorbent and in which non-condensable gases may occur, a purge device including a condenser connected to said system for receiving and segregating non-condensable gases, a water operated aspirator connected to said condenser, conduits for supplying water in a path of flow through the condenser and aspirator successively, and a check valve between the condenser and aspirator for permitting the flow of gases from the condenser to the aspirator while preventing the flow of gases from the aspirator to the condenser, the temperature and vapor pressure of the water in the aspirator varying in accordance with the presence or absence of non-condensable gases in the condenser to produce a pressure in the aspirator below or above the pressure at which media will flow from the condenser to the aspirator whereby the aspirator is operative to withdraw non-condensable gases from the condenser and through the check valve without withdrawing refrigerant vapor therefrom after the gases have been withdrawn.

9. In an absorption refrigeration system comprising a generator, a main condenser, an evaporator, an absorber, means interconnecting the elements to provide a closed circuit for the circulation of a refrigerant and absorbent, an auxiliary condenser connected to the main condenser adjacent the outlet therefrom, a water operated aspirator connected to the auxiliary condenser, conduits for supplying cooling water in a path of

flow through the auxiliary condenser and water operated aspirator successively, the temperature and vapor pressure of the water in the aspirator varying to produce a pressure in the latter above and below the pressure at which media will flow from the auxiliary condenser to the aspirator depending upon the amount of condensation occurring in the auxiliary condenser whereby the aspirator is operative to withdraw non-condensable gases from the auxiliary condenser without withdrawing any refrigerant vapor therefrom after the gases have been withdrawn.

10. In an absorption refrigeration system comprising a generator, a condenser, an evaporator, an absorber, means interconnecting the elements to provide a closed circuit for the circulation of a refrigerant and absorbent, means for transferring non-condensable gases from the absorber to the condenser, a water operated aspirator connected to the condenser, and means for supplying cooling water in a path of flow through the condenser and aspirator successively, the temperature and vapor pressure of the water in the aspirator varying to produce a pressure in the latter above and below the pressure at which media will flow from the condenser to the aspirator depending upon the amount of condensation of refrigerant vapor occurring in the condenser whereby the aspirator is operative to withdraw non-condensable gases from the condenser without withdrawing any refrigerant vapor therefrom after the gases have been withdrawn.

11. In an absorption refrigeration system comprising a generator, a main condenser, an evaporator, an absorber, means interconnecting the elements to provide a closed circuit for the circulation of a refrigerant and absorbent, means for transferring non-condensable gases from the various elements of the system to the main condenser, an auxiliary condenser connected to the main condenser adjacent its outlet, a water operated aspirator connected to the auxiliary condenser, conduits for supplying cooling water in a path of flow through the auxiliary condenser and water operated aspirator successively, the temperature and vapor pressure of the water in the aspirator varying to produce a pressure in the latter above and below the pressure at which media will flow from the auxiliary condenser to the aspirator depending upon the amount of condensation of refrigerant vapor occurring in the auxiliary condenser whereby the aspirator is operative to withdraw non-condensable gases from the auxiliary condenser without withdrawing any refrigerant vapor therefrom after the gases have been withdrawn.
